Primary Examiner — Austin Murphy(74) *Attorney, Agent, or Firm* — Haverstock & Owens LLP**CLAIM**

We claim the ornamental design for biaxial foldout tool, as shown and described.

DESCRIPTION

FIG. 1 illustrates a top perspective view of the biaxial foldout tool in a closed position;

FIG. 2 illustrates a first side perspective view of the biaxial foldout tool in a closed position;

FIG. 3 illustrates a bottom perspective view of the biaxial foldout tool in a closed position;

FIG. 4 illustrates a second side perspective view of the biaxial foldout tool in a closed position;

FIG. 5 illustrates the top perspective view of the biaxial foldout tool in a 180° open position; and,

FIG. 6 illustrates the top perspective view of the biaxial foldout tool in a 90° open position.
